UNITED STATES PATENT OFFICE.

HARRY J. MARTIN, OF FORT DODGE, IOWA.

GERBE AND LANCE PIECE FOR PYROTECHNICS.

1,291,584.

Specification of Letters Patent. Patented Jan. 14, 1919.

Application filed March 27, 1918. Serial No. 225,079.

To all whom it may concern:

Be it known that I, HARRY J. MARTIN, citizen of the United States of America, and resident of Fort Dodge, Webster County, Iowa, have invented a new and useful Improvement in Gerbe and Lance Pieces for Pyrotechnics, of which the following is a specification.

This application is a continuation in part of, and covers some features described in my application No. 124,009, filed October 4, 1916, to which reference hereby is made.

The object of this invention is to provide an improved construction for pyrotechnical set pieces, and particularly to facilitate packing the same in relatively small compass.

A further object of this invention is to provide improved means for compacting or contracting a set piece for storage or packing.

A further object of this invention is to provide a hub and spoke construction for gerbe and lance set pieces.

My invention consists in the construction, arrangement and combination of elements hereinafter set forth, pointed out in my claims and illustrated by the accompanying drawing, in which—

Figure 1 is a front elevation of one form of design constructed according to my invention and embodying my improvements.

Fig. 2 is a front elevation of another design, involving the gerbe as well as lance construction. Fig. 3 is a detail view of elements shown in Fig. 2.

Fig. 4 is a front elevation of another design, embodying my improvements and simulating the "red cross;" and Fig. 5 is a plan on an enlarged scale illustrating the manner of compacting or contracting the design of Fig. 4 for storage or shipment, the lances, fuse and hub not being shown.

In the particular construction according to Fig. 1 the numeral 10 designates a hub which may be of any desired shape, in this instance cylindrical, preferably formed of wood. The hub 10 is formed with a plurality of radial and circumferentially spaced sockets into which are doweled loosely the inner ends of spokes 11, 12, 13, 14, 15, in this instance five in number. Frame bars 16, 17 are mounted on opposite sides of

each spoke 11-15 inclusive, and are pivoted at one end each to the outer ends of said spokes by hinges 18. The hinges 18, which are to be used (flexed) in each instance but a very few times at most, preferably are formed of strips of pliable, non-combustible material, such as tin, thus providing an articulating means of cheap and simple construction. In this instance the frame bars 16, 17 are arranged to form the outline of a five-pointed star, and their inner ends are directed generally toward the center of the device but diverge from the spokes to which they are secured, the inner ends of the bars 16 meeting the inner ends of the adjacent bars 17 to form a continuous outline around the ends of the spokes. The adjacent ends of the bars 16, 17 are pivotally secured together by hinges 19 similar to the hinges 18; except that, in one instance, as in the space between spokes 13 and 14, or at any other convenient place, the hinging is omitted and the adjacent ends of the bars 16, 17 are detachably secured together by means of a tie wire 20, or other convenient and simple securing means. Pyrotechnic lances 21 of common form are mounted in the usual manner on the frame bars 16, 17 and are adapted, when illuminated, to form the outline of the star as defined by their arrangement on said bars. Lances 21 also may be mounted on the spokes. The lances 21 are connected by fuses 22 of quick-match made and arranged in a common and well known manner.

Thus is provided for the set piece a collapsible or contractible frame which, when expanded as shown, is sufficiently rigid and stable to suit the needs of the device and capable of being contracted to relatively small compass at times for packing and the like. To effect a contraction or collapse of the frame, the tie wire 20 first is detached, together with such portion of the fuse 22 as may cross the connected ends of the adjacent bars 16, 17. Then the spokes 11 to 15 inclusive are removed from the hub 10 by outward movement, and the spokes 13, 12 on one side are moved through an arc toward the spoke 11, while a similar action is applied to the spokes 14, 15 on the opposite side, thus bringing all of said spokes into substantially parallel relations, and in com-

pact position. Such action causes the bars 16, 17 secured to each spoke to approach such spoke and become substantially parallel thereto and lie against said spokes, the 5 successive spokes being separated in each instance by two frame bars. Such action of the several members is permitted, of course, by flexure of the hinges 18 and 19. The entire device may then be contained in a pack-
10 age having its dimensions defined by the length of the spokes, the height of the pyrotechnic devices, and the combined width of the several spokes and frame bars. The advantage of such a construction, and the saving in time, labor and expense, will be greatly appreciated by those skilled in this art, as compared to the present rigid construction of frame which must be packed without contraction, or at most after a single
15 fold through the center, in a package of considerable size and strength. The operation of extending the star, when it is desired to set it up, will be readily understood, it being necessary only to spread the spokes and frame bars, insert the dowels in the hub 10, secure the tie 20, connect the fuse 22, and secure the device to a support in any desired manner, as by nailing through the hub.

In the particular construction according to Fig. 2, a hub 10^a is provided and, in this instance, it is square in elevation and formed with four sockets, one on each side. Four spokes, 23, 24, 25, 26, are provided and are adapted to be doweled into the sockets 30 of the hub 10^a, and said spokes are, in this instance, of less length relative to the spokes 11-15. Frame bars 27, 28 are secured at their inner ends to adjacent sides of adjacent spokes and extend substantially parallel 35 with but materially beyond the outer ends of said spokes. Each pair of bars 27, 28 forms in a general way the outline of an equilateral triangle, which triangle is completed at the outer end of said bars 27, 28 by a cross frame bar, and each cross frame bar is formed in two parts 29, 30 of equal length, normally placed end to end in alignment to fill the space between said outer ends. The combination of the four equilateral triangles so formed produces the outline of the Maltese cross. The pivoting of the inner ends of the bars 27, 28 to the spokes 23, 24, 25, 26 preferably is by means 40 of hinges 31 constructed as above described; the pivoting of the outer ends of said bars to the adjacent ends of the parts 29, 30, respectively, is by means of similar hinges 32; while the adjacent ends of the parts 29, 30 are pivoted together by means of similar 45 hinges 33 placed on their outer faces so that the inner ends of said parts may move inwardly as indicated by the arrows in the drawing.

Lances 34 are mounted on the frame bars

27, 28, 29, 30 and, when illuminated, form 65 the outline of the Maltese cross and, to complete the design, I prefer to provide gerbes 35, in this instance four in number and secured to the ends of the spokes 23-26 inclusive, furnishing, when illuminated, a 70 sheaf of fire between each of the triangles above described. The lances 34 and gerbes 35 are connected by fuses 36 of quick-match in a common manner. To permit collapse and compacting of the piece, one of the 75 hinges 31, such as that between the spoke 25 and adjacent frame bar 27, is omitted and in its place is substituted a detachable fastener such as a tie wire 37. To collapse and compact or contract the device, the tie wire 80 37 is unfastened or removed, the spokes 23, 24, 25 and 26 are withdrawn from the hub 10^a, the several cross-bars (parts 29, 30) are articulated inwardly on the hinges 33, in the direction of the arrows, the fuse 36 is 85 disconnected, and the side frame bars 27, 28 are moved toward each other to collapse the various equilateral triangles. At the same time the spokes and several sets of frame bars are moved through arcs to substantially parallel relations and in the same plane until they occupy a compact position side by side. The entire device may then be contained in a package having its dimensions defined generally by the length 90 of the bars 27, 28, the height of the lances and fuse on the bars, and the combined width of all the spokes and frame bars.

In the particular construction according to Figs. 4 and 5, a hub 10^b is provided, preferably cylindrical in form and made with peripheral sockets, four in number. Four spokes 38, 39, 40, 41, are provided and are adapted to be doweled into the sockets of the hub 10^b and are provided with spikes 42 on their outer ends. Frame bars 43, 44 are arranged in pairs, in this instance four pairs spaced apart, and said bars are connected for flexing or articulation by hinges 45, of the character above described, placed 100 on the outer surfaces of their adjacent ends. The frame bars 43, 44, in pairs, are placed and arranged to form a broken outline of a Greek cross, and end bars, each formed of two parts 45, 46 placed end to end in alignment and connected together by hinges 47 of the character above described mounted on their outer faces, are positioned to supply the broken parts of said outline; and the outer ends of said end bars (parts 45, 46) 110 are pivoted to the outer ends of the frame bars 43, 44 respectively by hinges 48, 49, like unto the other hinges described, placed on the inner surfaces of adjacent end portions. Different indices are applied to the 115 hinges 48, 49 for the reason that the hinges 48 preferably are formed with holes through which the spikes 42 may project when the

elements are assembled as shown in Fig. 4, to connect the frame and end bars to the hub 10^b. In said Fig. 4, the spokes are indicated by single lines to avoid confusion, the scale being small, but the spokes are shown more in detail in Fig. 5, and such detail is to guide and control. One of the hinges 47 preferably is substituted by a different hinge 47^a of common loose-pin type, 10 to provide means for separating the outline at times. Pyrotechnic lances 50 are mounted on the frame bars 43, 44, and parts 45, 46, in a common manner and are adapted, when illuminated, to form the outline of the 15 Greek cross and the proportions and relations of parts are such as to produce an illustration now popularly known as the red cross. The lances 50 are connected by a fuse 51 of quick-match made and arranged in a 20 common and well known manner. To collapse and compact or contract the device, the loose pin of the hinge 47^a is removed, the fuse 51 is divided adjacent thereto, the spokes 38, 39, 40, 41 are withdrawn from 25 the hub 10^b, the several end bars are articulated on the hinges 47, in the direction indicated by arrows, parts 45, 46 of the end bars articulate on the hinges 48, 49, the hinges 48 folding across and along-side of 30 the outer ends of the spokes 38, 39, 40, 41, and the bars are moved toward each other and toward the spokes, and the spokes are moved toward each other, all through arcs and in the same plane, into substantially 35 parallel relations as shown in Fig. 5. The entire device may then be contained in a package having its dimensions defined generally by the length of the spokes, the height of the lances and fuses and the 40 combined width of all the spokes and frame bars.

It will be understood that various other combinations and arrangements of hub, spokes and frame bars may be had, to form 45 various designs and outlines, without departing from the spirit of my invention; and I do not wish to be understood as limiting myself to the precise construction and arrangement herein shown and described. 50 The essence of the invention lies in the provision of spokes removably secured to a central hub and carrying pivoted frame bars, all of which may be compacted by movement in the same plane to form a package of materially less width than the width 55 of the complete piece when extended.

I claim as my invention—

1. A device of the class described, comprising a hub, spokes detachably secured to and radiating from said hub, frame bars pivoted to said spokes and forming an outline or design, and pyrotechnic devices carried by said frame bars.
2. A device of the class described, com-

prising a hub, spokes detachably secured to 65 and radiating from said hub, frame bars pivotally secured to said spokes and to each other, and pyrotechnic devices carried by said frame bars.

3. A device of the class described, comprising a hub, spokes detachably secured to and radiating from said hub, frame bars pivotally secured to said spokes and to each other, said connected spokes and frame bars being adapted to be brought into compact 70 parallel relations upon removal of said spokes from said hub, and pyrotechnic devices carried by said frame bars.

4. A device of the class described, comprising a hub, spokes detachably secured to and radiating from said hub, frame bars pivotally secured to said spokes, said connected spokes and frame bars being adapted for movement in a common plane to compact, substantially parallel relations by removal of said spokes from said hub, and pyrotechnic devices carried by said frame bars.

5. A device of the class described, comprising a hub, a plurality of spokes detachably secured to said hub, frame bars pivotally secured to said spokes and pivotally connected to form an outline, and pyrotechnic devices carried by said frame bars, said frame bars being detachable at one 90 point and movable in a plane to compact parallel relations, upon removal of said spokes from said hub, whereby said spokes and bars may lie side by side in compact 95 relations in the same plane.

6. A device of the class described, comprising, a hub, spokes secured to and radiating from said hub, connected frame bars adapted removably and replaceably to be secured to said spokes and, when so secured, forming an outline or design, and pyrotechnic devices carried by said frame bars.

7. A device of the class described, comprising a hub, spokes secured to and radiating from said hub, connected frame bars adapted to be detachably secured to said spokes and, when so secured, forming an outline or design, adjacent ends of some of said frame bars being hinged together between said spokes, and pyrotechnic devices carried by said frame bars.

8. A device of the class described, comprising a hub, spokes secured to and radiating from said hub, connected frame bars adapted to be detachably secured to said spokes and, when so secured, forming an outline or design, and pyrotechnic devices carried by said frame bars and spokes.

9. In a device of the class described, frame bars pivotally secured to each other 125 and forming an outline or design, said frame bars being detachable at one point and movable in a plane and adapted to be

brought into compact parallel relations upon separation at one point, and pyrotechnic devices carried by said frame bars.

10. In a device of the class described, 5 frame bars pivotally secured to each other and forming an outline or design, said frame bars being adapted to be brought into compact parallel relations, upon separation

at one point, by movement through an arc in a common plane, and pyrotechnic devices 10 carried by said frame bars.

Signed at Fort Dodge, in the county of Webster and State of Iowa, this 18th day of March, 1918.

HARRY J. MARTIN.
